RAMMING DEVICE FOR RAMMING A ROUND OF AMMUNITION INTO A GUN BARREL

Henry Wilhelm Aldrin, Bofors, Sweden, assignor to Aktiebolaget Bofors, Bofors, Sweden, a company of Sweden

Application June 9, 1958, Serial No. 740,910

Claims priority, application Sweden June 8, 1957

4 Claims. (Cl. 89—47)

The present invention relates to a ramming device for ramming a round of ammunition into a gun barrel, and more particularly into the barrel of an automatic recoiling gun.

Ramming devices for automatic guns generally comprise a rammer which is slidable in the direction of the axis of the bore of the gun barrel and which engages the round, or more specifically the bottom flange of the cartridge casing, thereby ramming the round home. In ramming devices as heretofore known, the rammer is actuated by one or more strong helical springs, the free ends of which when released move in the same direction as the rammer and must travel through about the same distance, whereby close limitations are imposed upon the possible dimensions of the spring or springs. As is well known, the potential energy that can be stored in a compression loaded spring is substantially proportional to the weight of the spring and substantially independent of the dimensions of the spring.

In a ramming device of any design, a portion of the stored spring energy is consumed by the force required for the acceleration of the moving spring end and the rammer. Obviously this portion of the energy is lost for the intended action, namely the ramming of the round. Accordingly, it is desirable to keep the force required for accelerating the moving spring end and the rammer as low as possible, or in other words, to utilize a maximum portion of the available total force for ramming a round.

It is an object of the present invention to provide a novel and improved ramming device of the general kind above referred to, in which the ratio of energy used for acceleration of the spring or rammer and acceleration of the round respectively is highly in favor of ramming the round.

Another object of the invention is to provide a novel and improved ramming device in which the spring energy is utilized to the fullest possible extent by transmitting the spring energy to the rammer by means of a lever arrangement which acts upon the rammer during part of the rammer movement at a right angle, that is in the most favorable direction of force.

Still another object of the invention is to provide a novel and improved ramming device design in which the distance of the required spring movement is shorter than the distance of the required rammer movement. As a result, the actuating spring can obtain the form of a short and heavy spring which affords the advantage of highly favorable spring conditions due to the aforementioned weight dependency of the spring force.

Other and further objects, features and advantages of the invention will be pointed out hereinafter and set forth in the appended claims forming part of the application.

In the accompanying drawing a preferred embodiment of the invention is shown by way of illustration and not by way of limitation.

In the drawing:

2

Fig. 1 is an elevational sectional view of a ramming device according to the invention, and

Fig. 2 shows a perspective view of the ramming device of Fig. 1.

5 Referring now to the figures in detail, the exemplified ramming device comprises a lever 1 which is pivotal about a pivot 2 supported on a casing part of the ramming device. A short and heavy pressure spring 3 coacts with lever 1 and seeks to turn the same in counter-clockwise direction as shown. Lever 1 is restrained against the action of spring 3 by means of a pawl 4 engaging the lever. The pawl is pivotally supported on a locking bridge 5 which in turn is pivotally mounted by means of a pivot 6 secured to a part of the casing of the ramming device. Bridge 5 is prevented from turning in counter-clockwise direction by a lug 7 and is prevented from turning clockwise by a pivotal pawl 8 engaging the bridge. By turning the pawl 8 in clockwise direction, bridge 5 is released for upwards movement, and the lever 1 will exert a torque upon the bridge in clockwise directions owing to the fact that the contact surface between pawl 4 and arm 1 is not at right angles to a line through the surface and the pivot center of bridge 5. Pawl 8 may be turned by any suitable means. As can be seen in Fig. 2, lever 1

10 comprises two parallel arms which are both supported on pivot shaft 2. The free end of each of the two arms is recessed at 9 to receive a pin 10 which is guided in a slot 11 extending substantially in the direction of the intended ramming movement. The just described arrangement of

15 slot 11 is duplicated for the second arm of lever 1.

Pin 10 supports the rammer 12. The rammer is in the form of a two-arm lever, pin 10 constituting the fulcrum of the rammer. The end portion of the respective arm of the rammer is raised to form a lip or lug engaging the bottom flange 13 of the cartridge casing of the round 14 to be rammed. The raised lug of the rammer is preferably made of resilient material such as spring steel. The other arm of the rammer terminates in a lug 15 riding upon a guide surface 30 formed on a part of the ramming device.

20 Let it now be assumed that all the components are in the position shown in Figs. 1 and 2 in full lines and that lever 1 is released from pawl 4. Then the spring will abruptly turn lever 1 in counter-clockwise direction as shown. The turning of the lever will carry along the rammer whereby the round 14 is rammed at a correspondingly high speed.

25 If flange 13 should not be in direct abutment with the raised lug of the rammer at the beginning of the ramming movement, the lug will readily absorb the shock of the contact between the rammer and the round due to the resiliency of the lug thereby avoiding damage to the flange of the cartridge casing. The pressure exerted by the rammer upon flange 13 and vice versa will tend to turn the rammer in a clockwise direction as seen, whereby lug 15 is pressed against the guide surface 30 thus retaining the rammer in the appropriate position for ramming.

30 As lever 1 approaches the end of its ramming movement, which is indicated in Fig. 1 in dotted lines, the lever will engage a buffer 16 which gradually absorbs the residual energy of the lever movement.

35 In order to cock the ramming device, pivot shaft 2 supports a cocking lever 17, a recess 18 of which is engaged by a roller 19 supported by one arm 20 of a two-arm lever rotatable about a pivot 23 supported on the ramming device. The other arm 21 of the lever mounts a roller 22 which is engaged by a suitable curved guide (not shown) on the breech ring 24 on the barrel of a recoiling gun during the recoil movement of the gun. The gun barrel should be visualized as being of conventional design and is not shown to simplify the illustration. As a result, roller 22 will be forced downwardly whereby lever 1 is

turned through lever 17 into the direction in which spring 3 is compressed. When the lever has returned into the position shown in Figs. 1 and 2 in full lines, spring 3 is loaded and pawl 4 again retains lever 1 in its cocked position.

During the last part of the just described cocking motion, a lug 25 on the rammer engages a second stationary buffer 26 which is mounted on the elevating mass of the gun.

During the ramming operation the rammer 12, 15 will be kept in the right position owing to its engagement with the round. During the cocking motion the rammer 12, 15 is allowed to turn freely around the pivot 10. Only during the last part of the cocking motion the rammer will be kept in a position ready for engagement with a round owing to the contact between lug 25 and buffer 26.

The buffer 26 cannot be replaced by an unmovable lug, as it must allow for an extra movement of arm 1 sufficient for the locking operation. Of course, the rammer 12 could be kept into the right position by means of a spring device following the arm 1, but in such case the masses to be accelerated during the ramming operation would increase.

While the invention has been described in detail with respect to a certain now preferred example and embodiment of the invention it will be understood by those skilled in the art, after understanding the invention, that various changes and modifications may be made without departing from the spirit and scope of the invention, and it is intended therefore, to cover all such changes and modifications in the appended claims.

What is claimed as new and desired to be secured by Letters Patent is:

1. A ramming device for ramming rounds of ammunition into the breech of a gun comprising, in combination, a casing, a rammer slidably supported upon said casing for movement along a linear path, an actuating lever, a pivot mount carried by said casing out of said linear path of movement of said rammer pivotally supporting one end

of said lever for movement between two angularly displaced limit positions in a plane substantially parallel to said slide path of said rammer, the opposite end of said actuating lever being drivingly connected to said rammer for displacing said rammer along said slide path in response to said pivotal movement of said lever, said lever during movement between said limit positions passing through a right angle position relative to said rammer in said slide path, spring means acting between said casing and said lever intermediate the ends of said lever in a direction substantially parallel to said slide path of said rammer, and releasable lock means releasably securing said lever in one cocked limit position of said rammer against said spring means.

15 2. A ramming device according to claim 1 and also comprising a rammer cocking means engageable with said lever for pivoting said lever into said cocked position against the action of the spring means.

20 3. A ramming device according to claim 1 wherein said rammer comprises a two-arm lever, a pivot shaft pivotally supporting said lever at an intermediate point to form the two arms thereof, said shaft being engaged by said actuating lever, one of said rammer arms having a lug engageable with a round during the ramming operation, the other rammer arm abutting against and restrained by a guiding surface on the ramming device, the operational pressure between said lug and the round engaged by the lug pressing said other lever arm toward said guiding surface.

25 4. A ramming device according to claim 3 and further comprising buffer means stationarily mounted relative to the lever, said lever abutting against said buffer means in a predetermined position of displacement.
